INTERMITTENT FILM DRIVING AND
FRAMING APPARATUSPhilmore F. Sperry, Chicago, Ill., assignor to Re-
vere Camera Company, Chicago, Ill., a corpora-
tion of Delaware

Application July 26, 1939, Serial No. 265,545

12 Claims. (Cl. 88—18.4)

This invention relates to improved means for giving a film an intermittent movement through a projector or the like with each frame or picture section of the film in centered position with respect to the ray of light employed for projection purposes, and it has for its object the provision of a new and improved form and arrangement of parts by which improved operation shall be attained. It is one of the objects of this invention to provide a simple arrangement of framing or centering means by which the film can be easily and quickly brought to its desired operating position without stopping the operation of the machine or in any other way interfering with such operation.

In the simple and effective construction as illustrated in the drawings, a resilient shuttle arm is employed adapted to swing about a pivotal axis with a spring member opposing the swinging movement in one direction, together with two co-operating actuating devices one of which gives said shuttle arm a swinging movement about its pivotal axis against the action of said spring member and the other of which moves the arm at right angles to said swinging movement against the resiliency of the arm itself. In the form of construction as shown, the actuating device by which the arm is given its swinging movement about its pivotal axis is itself adapted to be adjusted in the same direction as that in which such actuating device moves the shuttle arm. By an adjustment of this actuating device, the length of the stroke of the shuttle arm remains unchanged, but the point at which the effective stroke of the arm terminates is changed.

It is another object of this invention to improve devices of this type in sundry details herein-after pointed out. The preferred means by which the several objects have been attained are illustrated in the accompanying drawings, in which—

Fig. 1 is a vertical sectional view taken substantially at the line 1—1 of Fig. 2 showing the preferred form of construction;

Fig. 2 is a horizontal sectional view taken substantially at the line 2—2 of Fig. 1;

Fig. 3 is a top plan view of the shuttle arm and its closely associated parts;

Fig. 4 is a vertical sectional view taken substantially at the front face of the shuttle arm and looking backwardly, with many of the associated parts omitted;

Fig. 5 is a view on an enlarged scale similar to a portion of Fig. 1 but showing in solid and dotted lines the limit operating positions of the shuttle arm; and

Fig. 6 is a view similar to Fig. 5 likewise showing two limit positions of the shuttle arm but with one of the actuating devices for the shuttle arm moved to a different position of adjustment.

Referring now to the several figures of the drawings, in which corresponding parts are indicated by the same reference characters, 10 indicates a framework in the form of a housing pivotally mounted by means of a bolt 11 upon a base 12, only a fragmentary portion of which 10 is shown in Fig. 1. The housing 10 comprises a plurality of parts or sections including a motor housing 13, a fan housing 14, a lamp housing 15, and a central housing portion 16 communicating directly or indirectly with the other sections mentioned. As is best shown in Fig. 2, a motor shaft 17 extends through the wall of the partition between the housing sections 13 and 16, such motor shaft having a driving wheel 18 fixedly mounted thereon within the housing section 16 and having fans 19 and 20 fixedly mounted thereon so as to be operated by the motor. The arrangement is such that the fan 19 forces air inwardly through the motor and thence toward the right in Fig. 2 so as to cool the film and the operating means 25 for the film. The fan 20 forces a considerable volume of air into the lamp housing 15 so as to have a cooling effect upon the lamp 21 of any suitable type in said housing. In front of the lamp housing 15, a lens housing 22 is provided opposite an opening 23 through which a beam of light passes for projection purposes. A swingingly mounted shutter 24 is provided adapted to cover the opening 23 when the operation of the projector is terminated.

Means is provided for transmitting power from the driving wheel 18 comprising a second driving wheel 25 which is rotatably mounted upon an arm 26 so as to be movable into and out of operative engagement with the driving wheel 18. A pinion 27 is mounted so as to rotate with the driving wheel 25, such pinion being in meshing engagement with a gear 28 which in turn meshes with a gear 29 fixedly mounted upon a drive shaft 30. At its rear end portion, the shaft 30 is provided with a shutter 31 of the usual type employed in projectors for intermittently cutting off the passage of the ray of light through the opening 23.

The parts so far described form in and of themselves no part of the present invention and it is believed accordingly that it is unnecessary to describe them or their operation more in detail herein.

The means for driving a film intermittently

25

20

15

10

5

past the opening 23 comprises a shuttle arm 32 pivotally mounted upon a machine screw 33 extending into a lug 34 carried by the wall of the housing portion 16. In the arrangement shown, 8 the shuttle arm 32 is in the form of a thin strip having a turned end portion 35 adapted to engage openings 36 in a film 37 threaded through the machine, as shown in Fig. 5. The strip 32 is of considerable width so as to be comparatively 10 stiff vertically, the strip having sufficient resiliency to enable it to be moved readily sidewise from its normal position,—that is to say, in a direction at right angles to the direction in which the arm has its pivotal movement about the bolt 15 33. A flat spring 38 carried by the wall of the housing 16 normally presses the shuttle arm 32 upwardly toward the shaft 30.

For giving the shuttle arm 32 the desired movements for actuating the film 37 intermittently, a 20 cam 39 has been provided on the face of the gear 29, as is best shown in Fig. 4, such cam 39 being adapted to engage a lug 40 carried by the arm 32. The arrangement is such that upon each 25 revolution of the shaft 30 the arm 32 is moved for projecting the turned end portion 35 of the arm through the opening 41 for engagement with one of the openings 36 in the film 37.

In the improved arrangement illustrated in 30 the drawings, a short arm 42 is pivotally mounted about the shaft 30 having a gear 43 rotatably mounted upon its free end by means of a short shaft 44, such gear 43 meshing with the gear 29 and being of the same size so as to cause the shaft 44 to rotate at the same speed 35 as that of the shaft 30. Upon the shaft 44, a cam or arm 45 is fixedly mounted in position to engage a lug 46 carried by the shuttle arm 32. The cam or arm 45 is adapted by engagement with the lug 46 to give the shuttle arm 40 32 a downward movement against the action of the spring 38.

For holding the arm 42 normally in raised position, a coiled spring 47 has been provided, bearing at its upper end against the arm 42 45 and at its lower end against the adjacent portion of the framework. For moving the arm 42 downwardly against the action of the spring 47 into the desired adjusted position vertically, a pin 48 is provided, as is best shown in Fig. 1, 50 such pin 48 having screw-threaded engagement with the framework near its upper end portion so as to be readily adjustable vertically. Upon the upper end of the pin 48 outside of the housing, a knurled head 49 is provided, as is clearly 55 shown in Fig. 1. A set screw 50 is arranged for applying pressure at one side of the pin 48 for holding it in its adjusted position.

The arrangement of the parts is such that when the shaft 30 is rotated in counterclockwise direction in Fig. 4 for projecting the end portion 35 of the shuttle arm through the opening 41 into engagement with the film 37, the arm or cam 45 is at the same instant ready by engagement with the lug 46 to give the shuttle arm 60 a downward swinging movement about the pivot pin 33. The arrangement is such that at the end of the desired downward movement of the shuttle arm the cam 39 clears the lug 40 so as to permit the shuttle arm to move by its own 65 resiliency back to its normal position out of engagement with the film 37. Shortly after the release of the arm from the film, the arm 45 passes out of engagement with the lug 46 so as to permit the spring 38 to move the shuttle arm 70 again to its raised position ready for engage- 75

ment with the next adjacent opening 36 in the film 37 for the next succeeding intermittent movement of the film.

As is clearly shown in Fig. 1, the opening 23 is precisely centered with respect to the lens 5 housing 22 so that the axis of the lens passes directly through the center of the frame or picture section of the film under normal conditions. If it is found at any time in the operation of the machine that the film is not properly framed, 10 the pin 48 can be very quickly and easily rotated in the proper direction for moving the arm 42 either upwardly or downwardly as may be required for bringing the center of the picture section directly to the axis of the lens system. 15

In Fig. 5, the uppermost limit position of the shuttle arm 32 is shown in solid lines, with the corresponding lowermost position shown in dotted lines, with the arm 42 adjusted to have a 20 very slight upward trend from the shaft 30. In Fig. 6, a similar arrangement is shown with the arm illustrated in its uppermost position by solid lines and illustrated in its lowermost position by dotted lines but with the arm 42 adjusted 25 downwardly as compared with the position of the arm as shown in Fig. 5. As will be appreciated from an inspection of these two figures, any desired adjustment may be had between the limits as shown by the two figures so as to have 30 the film framed properly at all times, and with the axis of the lens system passing at all times through the center of the several picture sections or frames.

While the form and arrangement of parts as 35 illustrated in the drawings and as above described are the preferred form of apparatus, the invention is not to be limited thereto except so far as the claims may be so limited, it being understood that changes might well be 40 made in the form and arrangement of parts without departing from the spirit of the invention. 45

I claim:

1. A film driving means comprising in combination a frame, a shuttle arm in the form of a plate substantially rigid edgewise pivotally mounted so as to swing edgewise and arranged so as to be movable also facewise, a lug carried by said shuttle arm adapted by engagement with a film to move the film longitudinally, means rotatable on a fixed axis on said frame for giving said arm facewise movements for controlling the engagement of said lug with said film, a support movably mounted adjacent to said axis on said frame, means rotatably mounted on said support adapted by rotary movement to give said arm edgewise movements through a predetermined range, and means for moving said support to different positions on said frame for changing the limits to which said arm is moved edgewise by said second-named rotatable means. 55

2. A film driving means comprising in combination a frame, a shuttle arm in the form of a plate substantially rigid edgewise pivotally mounted so as to swing edgewise and arranged so as to be movable also facewise, a lug carried by said shuttle arm adapted by engagement with a film to move the film longitudinally, means rotatable on a fixed axis on said frame for giving said arm facewise movements for controlling the engagement of said lug with said film, a support movably mounted adjacent to said axis on said frame, means rotatably mounted on said support adapted by rotary movement 60

- to give said arm edgewise movements through a predetermined range, a spring for moving said support yieldingly in one direction, and a set screw for moving said support in the opposite direction against the action of said spring for changing the limits to which said arm is moved edgewise by said second-named rotatable means.
3. A film driving means comprising in combination a frame, a shuttle arm in the form of a plate substantially rigid edgewise pivotally mounted so as to swing vertically edgewise and arranged so as to be movable also sidewise, a lug carried by said shuttle arm adapted by engagement with a film to move the film longitudinally, means comprising a cam rotatable on a fixed axis on said frame for giving said arm sidewise movements for controlling the engagement of said lug with said film, a shaft rotatably mounted on said frame adjacent to said cam means so as to be movable vertically with respect to said cam means, means comprising a second cam mounted on said shaft so as to rotate therewith and adapted by rotary movement of the cam to give said arm edgewise movements vertically through a predetermined range, and means for moving said shaft vertically to different positions on said frame for changing the upper and lower limits between which said arm is moved by said second cam means.
4. A film driving means comprising in combination a frame, a shuttle arm in the form of a plate substantially rigid edgewise pivotally mounted so as to swing vertically edgewise and arranged so as to be movable also sidewise, a lug carried by said shuttle arm adapted by engagement with a film to move the film longitudinally, means comprising a cam rotatable on a fixed axis on said frame for giving said arm sidewise movements for controlling the engagement of said lug with said film, a shaft rotatably mounted on said frame adjacent to said cam means so as to be movable vertically with respect to said cam means, means comprising a second cam mounted on said shaft so as to rotate therewith and adapted by rotary movement of the cam to give said arm edgewise movements vertically through a predetermined range, intermeshing gears connected with said cams respectively for causing them to move at the same speed of rotation, and means for moving said shaft vertically to different positions on said frame for changing the upper and lower limits between which said arm is moved by said second cam means.
5. A film driving means comprising in combination a frame, a shuttle arm in the form of a plate substantially rigid edgewise pivotally mounted so as to swing vertically edgewise and arranged so as to be movable also sidewise, a lug carried by said shuttle arm adapted by engagement with a film to move the film longitudinally, means comprising a cam rotatable on a fixed axis on said frame for giving said arm sidewise movements for controlling the engagement of said lug with said film, a shaft rotatably mounted on said frame adjacent to said cam means so as to be movable vertically with respect to said cam means, means comprising a second cam mounted on said shaft so as to rotate therewith and adapted by rotary movement of the cam to give said arm edgewise movements vertically through a predetermined range, intermeshing gears connected with said cams respectively in such relation as to cause said shuttle arm to move edgewise in one direction in operative driv-
- ing engagement with said film and to move edgewise in the opposite direction clear of the film, and means for moving said shaft vertically to different positions on said frame for changing the upper and lower limits between which said shuttle arm is moved by said second cam means.
6. A film driving means comprising in combination a shuttle arm movably mounted so as to be adapted to swing in one direction and arranged so as to be movable at right angles to said swinging movement and normally held yieldingly at one limit of its motion in each of said directions, means carried by said shuttle arm for moving a film lengthwise, an actuating member adapted by an operative movement to give said arm a movement in one of said two directions, a second arm movably mounted adjacent to said actuating member, and a second actuating member carried by said second arm and adjustable therewith adapted by an operative movement in any adjusted position of said second arm to give said first-named arm a movement in the other of said two directions.
7. A film driving means comprising in combination a resilient shuttle arm movably mounted so as to be adapted to swing in one direction and arranged so as to be movable at right angles to said swinging movement and normally held yieldingly at one limit of its motion in each of said directions, means carried by said shuttle arm for moving a film lengthwise, an actuating member adapted by a rotary movement to give said arm a movement in one of said two directions, a second arm pivotally mounted on the axis of said actuating member, and a second actuating member carried by said second arm and adjustable therewith adapted by rotary movement in any adjusted position of the second arm to give said first-named arm a movement in the other of said two directions.
8. A film driving means comprising in combination a shuttle arm movably mounted so as to be adapted to swing in one direction and arranged so as to be movable at right angles to said swinging movement and normally held yieldingly at one limit of its motion in each of said directions, means carried by said shuttle arm for moving a film lengthwise, an actuating member adapted by a rotary movement to give said arm a movement in one of said two directions, a second arm pivotally mounted on the axis of said actuating member, a second actuating member carried by said second arm and adjustable therewith adapted by rotary movement in the opposite direction in any adjusted position of said second arm to give said first-named arm a movement in the other of said two directions, and means for driving said actuating members in opposite directions at the same speed of rotation.
9. A film driving means comprising in combination a shuttle arm movably mounted so as to be adapted to swing in one direction and arranged so as to be movable at right angles to said swinging movement and normally held yieldingly at one limit of its motion in each of said directions, means carried by said shuttle arm for moving a film lengthwise, an actuating member adapted by a rotary movement to give said arm a movement in one of said two directions, a second arm pivotally mounted on the axis of said actuating member, a second actuating member rotatably mounted on said second arm and adjustable therewith adapted by rotary movement in the opposite direction in any adjusted position

- of said second arm to give said first-named arm a movement in the other of said two directions, and adjustable means adapted by engagement with said second arm to hold said second actuating member in adjusted position with respect to said first-named actuating member for changing the termination point of the movement of said shuttle arm by said second actuating member.
10. 10. A film driving means comprising in combination a shuttle arm movably mounted so as to be adapted to swing in one direction and arranged so as to be movable at right angles to said swinging movement and normally held yieldingly at one limit of its motion in each of said directions, means carried by said shuttle arm for moving a film lengthwise, an actuating member adapted by a rotary movement to give said arm a movement in one of said two directions, a second arm pivotally mounted on the axis of said actuating member, a second actuating member carried by said second arm and adjustable therewith adapted by rotary movement in the opposite direction in any adjusted position of said second arm to give said first-named arm a movement in the other of said two directions, intermeshing gears of the same effective size connecting said two actuating members, and means for driving said actuating members in timed relation to the normal movement of a film through a projector.
11. A film driving means comprising in combination a resilient shuttle arm pivotally mounted at one end so as to swing edgewise and adapted by its own resiliency to bend slightly sidewise and of comparatively great stiffness edgewise, means carried by said shuttle arm for moving a film lengthwise, a spring normally holding said arm at one limit of its swinging movement about its pivotal axis, an actuating member adapted by a rotary movement to give said arm a movement sidewise, a second arm pivotally mounted on the axis of said actuating member, and a second actuating member carried by said second arm and adjustable therewith adapted by rotary movement in any adjusted position of said second arm to give said first-named arm a movement edgewise against the action of said spring.
12. A film driving means comprising in combination a resilient shuttle arm pivotally mounted at one end so as to swing edgewise and adapted by its own resiliency to bend slightly sidewise and of comparatively great stiffness edgewise, means carried by said shuttle arm for moving a film lengthwise, a spring normally holding said arm at one limit of its swinging movement about its pivotal axis, a second arm pivotally mounted adjacent to said first-named arm so as to swing in the same direction, a gear rotatably mounted on the axis on which said second arm is mounted, a second gear rotatably mounted on said second arm so as to mesh with said first-named gear, a cam on said first-named gear adapted by engagement with said first-named arm to give said arm a movement sidewise against the resiliency of the arm, and a second cam on said second gear adapted by engagement with said first-named arm in any adjusted position of said second arm to give said first-named arm a swinging movement against the action of said spring.

PHILMORE F. SPERRY. 35
